UNITED STATES PATENT OFFICE

117,730

DESIGN FOR AN AGE INDICATING NUMERAL FOR BIRTHDAY CAKES

Frances Fuller, New York, N. Y.

Application May 20, 1939, Serial No. 85,103

Term of patent 7 years

To all whom it may concern:

Be it known that I, Frances Fuller, a citizen of the United States and resident of the Borough of Manhattan, city, county, and State of New York, have invented a new, original, and ornamental Design for Age Indicating Numerals for Birthday Cakes, of which the following is a specification, reference being had to the accompanying drawing, forming part thereof.

Fig. 1 is a front elevational view of an age indicating numeral for birthday cakes showing my design; and

Fig. 2 is a front perspective view of the numeral shown in Fig. 1.

I claim:

The ornamental design for an age indicating numeral for birthday cakes, as shown.

FRANCES FULLER.
